UNITED STATES PATENT OFFICE.

MORRIS P. HOLMES, OF CLAREMONT, NEW HAMPSHIRE, ASSIGNOR TO SULLIVAN MACHINERY COMPANY, A CORPORATION OF MASSACHUSETTS.

MINING APPARATUS.

Application filed October 22, 1924. Serial No. 745,252.

My invention relates to mining apparatus.

An object of my invention is to provide an improved mining apparatus. A further object of my invention is to provide an improved mining apparatus especially adapted to cut vertical downwardly disposed kerfs in the coal strata. A still further object of my invention is to provide an improved mining apparatus wherein a flexibly fed mining machine of the pivoted bar type, herein of standard form, may be supported on its side in an improved manner to operate in accordance with the "strip or open pit" system of mining machine. Still another object of my invention is to provide an improved mining apparatus adapted to operate in accordance with the "strip or open pit" method of mining wherein the machine may be supported in an improved manner and bodily adjusted relative to the support. Still another object of my invention is to provide an improved mining apparatus provided with a cutter bar swingable in a vertical plane having improved supporting means upon which the machine is pivoted and bodily adjustable relative thereto. These and other objects and advantages of my invention will, however, hereinafter more fully appear.

In the accompanying drawings I have shown for purposes of illustration one form which my invention may assume in practice.

In these drawings,—

Fig. 1 is a side elevation of a mining apparatus constructed in accordance with one illustrative embodiment of my invention, the machine and cutter bar being shown in a plurality of positions.

Fig. 2 is an end elevational view of Fig. 1, the view being partially in section to facilitate illustration.

Fig. 3 is a vertical transverse sectional view taken substantially on line 3—3 of Fig. 1 through a portion of my improved adjusting means.

Fig. 4 is a vertical transverse sectional view taken substantially on line 4—4 of Fig. 1.

In this illustrative form of my invention I have shown a mining machine, generally designated 1, herein of a standard flexibly fed longwall type, having a longitudinally extending frame 2 which is comprised of a motor section 3, a feed section 4, and a cutting mechanism carrying section 5, the feed

and cutter carrying sections being disposed at opposite ends of the motor section 3 and rigidly connected thereto in any suitable manner. The frame section 2 is disposed on its side 6 with its bottom plate 7 disposed in a vertical plane on a skid or support, generally designated 8, of improved form to be hereinafter described. The mining machine 1 is adapted to be fed relative to a flexible feeding member 9, herein in the form of a feed chain, having its outer end fixed to a stationary extraneous abutment, not shown, and its inner end suitably guided on the machine by sheaves or rolls 10 journaled on horizontal transversely extending axes on the feed frame section 4. A feed operating member 11, herein in the form of a chain engaging sprocket, is rotatable on a transversely extending horizontal axis parallel to the axis of the rolls 10 and is adapted to draw in the feed chain 9 at a predetermined slow cutting speed and at a predetermined fast speed, the latter speed being utilized for hauling the machine about the mine surface and relative to a transport truck, not shown. It will herein be observed that the cutter bar 12 is pivoted on a transversely extending horizontal axis 13 parallel to the axis of the feed sprocket 11 and is provided with a cutter bit carrying cutter chain 14 adapted to be circulated about the outer edge of the bar. The feed chain 9 is adapted to be extended beneath the machine and connected to a two-part pivoted hook 15, indicated by dotted lines in Fig. 1 which is, in turn, adapted to engage a laterally extending abutment 15' formed integral with the cutter bar. When the feed chain is connected in such manner it is drawn in by the feed sprocket 11 at a slow or cutting speed, swinging the bar from the upper dotted line position in Fig. 1 downwardly into the coal strata, cutting a narrow vertical kerf and when the bar is disposed in a plane substantially perpendicular to the longitudinal axis of the machine frame 2, it is rigidly locked thereto by means of a locking pin 16 adapted to register with one of a plurality of horizontally disposed spaced openings 16' formed in a circular flange 17 which is adapted to guide the cutter bar during its swinging movement. It will herein be noted that the feed sprocket 11 and the cutter chain 14 are adapted to be driven by the motor 3 through suitable power transmission connections, not shown,

in any approved manner. The cutter bar may also be swung downwardly into the coal strata by means of the drag of the cutter bits and the weight of the bar.

- 5 As disclosed above, the mining machine 1 is adapted to be supported on its side on a skid 8 of improved form. In this improved construction it will be observed that a bottom plate 18 is provided adapted to engage 10 the surface of the mine and having curved front and rear ends 19 and 20, respectively, and slightly upturned curved side portions 21, thereby permitting the machine to slide freely on the surface of the mine. The side 15 6 of the mining machine has secured thereto a pair of laterally spaced longitudinally extending parallel plates 22 and 23 by means of screws 24. A longitudinally extending angle member 25 is provided to still more 20 securely hold the machine in position and is secured to the vertically disposed bottom plate 7 of the machine and the plate 22 by means of screws and rivets 26 and 27, respectively. A pair of laterally spaced, longitudinally extending, parallel angle members 28 and 29 are secured to the bottom plate 18 by means of suitable rivets. The support 8 is suitably braced by means of a longitudinally extending plate 28' and longitudinally spaced transverse plates 29', these plates being suitably riveted in position. As illustrated, upstanding laterally spaced bearing blocks 30 are suitably secured as by screws 31 to the angle member 29 and to a parallel angular member 32 secured to the bottom plate 18, and in these bearing blocks a transversely extending horizontal shaft 33 is carried located beneath the machine adjacent the center of gravity 40 thereof. Spacing plates 30' are interposed between the bearing blocks 30 and the angle members 29 and 32, respectively. Depending bearing blocks 34 are also secured to the plates 22 and 23 as by screws 35 and 45 also cooperate with the shaft 33. A plurality of transversely extending longitudinally spaced bracing members 36 are further provided having their flattened ends secured, as by rivets 37, to the transverse bracing members 29', and these bracing members 36 are provided with intermediate flattened portions 38 which engage the bottom plate 18 and are secured thereto by means of rivets 39. It will herein be observed that a relatively short angle member 40 is riveted to the bottom plate 18 adjacent one end thereof and is adapted to carry a bearing block 41. An oppositely disposed bearing block 42 is carried by the angle member 32 and in these bearing blocks a transversely extending pin 43 is carried, held in position by pin and washer connections 44. An upstanding rod 45 is pivoted, as at 46, on the pin 43 and is provided at its upper end with a threaded portion 47 adapt-

ed to engage a nut 48 secured, as by screws 49, to a suitable hand wheel 50. The hand wheel 50 is provided with a depending flanged portion 51 pivoted at 52 in a suitable bearing 53 in the form of a clamp. It will also be noted that the bearing member 53 is provided with a laterally disposed circular flanged portion 54 pivotally mounted within semi-circular bearing plate members 55 secured, as by screws 56, to the bottom plate 7 adjacent the upper forward end thereof. The nut 48 and the lower end of the portion 51 formed on the hand wheel 50 have threaded thereto upwardly and downwardly extending sleeves 57 and 58, respectively, through which the rod 45 extends and which are adapted to protect the threads 47. By suitable manipulation of the hand wheel 50 it will herein be noted that the machine 1 may be swung bodily relative to the bottom plate 18 as indicated by dotted lines in Fig. 1 about the pivot 33, consequently varying the position of the bar and the depth of the cut.

As a result of my improvement it will herein be noted that I have provided a mining machine especially adapted to operate in accordance with the "strip or open pit" method of mining having improved stable supporting means therefor and improved means for moving the machine relative to the supporting means for adjusting the position of the cutter bar consequently varying the depth of the cut. These and other advantages will be clearly apparent to those skilled in the art.

While I have in this application specifically described one form which my invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining apparatus, a skid slideable on the mine bottom, a mining machine provided with an angularly adjustable elongated cutter bar mounted for swinging movement in a vertical plane extending longitudinally of said skid and between the sides of the latter, said cutter bar being provided with cutting elements arranged to cut a kerf to admit said bar, and means to increase the cutting range of said machine in the plane of swinging movement of said bar comprising an adjustable pivotal mounting for said machine disposed beneath the latter on said skid.
2. In a mining apparatus, a skid slideable on the mine bottom, a mining machine provided with an angularly adjustable elongated cutter bar mounted for swinging

movement in a vertical plane extending longitudinally of said skid and between the sides of the latter, said cutter bar being provided with cutting elements arranged to cut 5 a kerf to admit said bar, and means to increase the cutting range of said machine in the plane of swinging movement of said bar comprising a horizontal pivotal mounting for said machine disposed beneath the latter on said skid.

3. In a mining apparatus, a skid slideable on the mine bottom, a mining machine provided with an angularly adjustable elongated cutter bar mounted for swinging 15 movement in a vertical plane extending longitudinally of said skid and between the sides of the latter, said cutter bar being provided with cutting elements arranged to cut a kerf to admit said bar, and means to increase the cutting range of said machine in the plane of swinging movement of said bar comprising an adjustable pivotal mounting for said machine disposed beneath the latter adjacent the center of gravity thereof 20 and carried on said skid.

4. In a mining apparatus, a skid slideable on the mine bottom, a mining machine provided with an angularly adjustable elongated cutter bar mounted for swinging 30 movement in a vertical plane extending longitudinally of said skid and between the sides of the latter, said cutter bar being provided with cutting elements arranged to cut a kerf to admit said bar, and means to increase the cutting range of said machine in the plane of swinging movement of said bar comprising a horizontal pivotal mounting for said machine disposed beneath the latter adjacent the center of gravity thereof 35 and carried directly on said skid.

5. In a mining apparatus, a skid slideable on the mine bottom, a mining machine provided with an angularly adjustable elongated cutter bar mounted for swinging 45 movement in a vertical plane extending longitudinally of said skid and between the sides of the latter, said cutter bar being provided with cutting elements arranged to cut a kerf to admit said bar, and means for angularly adjusting said machine relative to said skid to increase the cutting range of said machine in the plane of swinging movement of said bar comprising a transverse horizontal pivotal mounting for said 50 machine disposed beneath the latter adjacent the center of gravity thereof.

6. In a mining apparatus, a skid slideable on the mine bottom, a mining machine provided with an angularly adjustable elongated cutter bar mounted for swinging 60 movement in a vertical plane extending longitudinally of said skid and between the sides of the latter, said cutter bar being provided with cutting elements arranged to cut a kerf to admit said bar, and means for 65

angularly adjusting said machine relative to said skid to increase the cutting range of said machine in the plane of swinging movement of said bar comprising a transverse horizontal pivotal mounting for said machine disposed beneath the latter adjacent the center of gravity thereof, and adjusting means for effecting adjustment of said machine on said pivotal mounting. 70

7. In a mining apparatus, a skid slideable on the mine bottom, a mining machine provided with an angularly adjustable elongated cutter bar mounted for swinging movement in a vertical plane extending longitudinally of said skid and between the 80 sides of the latter, said cutter bar being provided with cutting elements arranged to cut a kerf to admit said bar, and means for adjusting said machine relative to said skid to increase the cutting range of said machine in the plane of swinging movement of said bar comprising a transverse horizontal pivotal mounting for said machine disposed beneath the latter, and adjusting means for effecting adjustment of said machine on said pivotal mounting. 85

8. In a mining apparatus, a mining machine normally cutting on its bottom and provided with an angularly adjustable elongated cutter bar provided with cutting elements arranged to cut a kerf to admit said bar, means for operating said machine with its bottom in a vertical plane comprising a skid disposed beneath said machine on which the side of the latter rests, said cutter bar being swingable in a vertical plane extending longitudinally of said skid and between the sides of the latter, and means to increase the cutting range of said machine in the plane of swinging movement 100 of said bar comprising an adjustable pivotal mounting for said machine disposed beneath the latter on said skid. 105

9. In a mining apparatus, a mining machine normally cutting on its bottom and provided with an angularly adjustable elongated cutter bar provided with cutting elements arranged to cut a kerf to admit said bar, means for operating said machine with its bottom in a vertical plane comprising a skid disposed beneath said machine on which the side of the latter rests, said cutter bar being swingable in a vertical plane extending longitudinally of said skid and between the sides of the latter, and means to increase 115 the cutting range of said machine in the plane of swinging movement of said bar comprising a horizontal pivotal mounting for said machine disposed beneath the latter on said skid. 120

10. In a mining apparatus, a mining machine normally cutting on its bottom and provided with an angularly adjustable elongated cutter bar provided with cutting elements arranged to cut a kerf to admit said 125

- 4
- 5 bar, means for operating said machine with its bottom in a vertical plane comprising a skid disposed beneath said machine on which the side of the latter rests, said cutter bar being swingable in a vertical plane extending longitudinally of said skid and between the sides of the latter, and means to increase the cutting range of said machine in the plane of swinging movement of said bar comprising a transverse horizontal pivotal mounting for said machine disposed beneath the latter on said skid.
- 10 11. In a mining apparatus, a mining machine normally cutting on its bottom and provided with an angularly adjustable elongated cutter bar provided with cutting elements arranged to cut a kerf to admit said bar, means for operating said machine with its bottom in a vertical plane comprising a skid disposed beneath said machine on which the side of the latter rests, said cutter bar being swingable in a vertical plane extending longitudinally of said skid and between the sides of the latter, and means for adjusting said machine angularly relative to said skid to increase the cutting range of said machine in the plane of swinging movement of said bar including a transverse pivot disposed beneath said machine adjacent the center of gravity thereof.
- 15 12. In a mining apparatus, a mining machine normally cutting on its bottom and provided with an angularly adjustable elongated cutter bar provided with cutting elements arranged to cut a kerf to admit said bar, means for operating said machine with its bottom in a vertical plane comprising a skid disposed beneath said machine on which the side of the latter rests, said cutter bar being swingable in a vertical plane extending longitudinally of said skid and between the sides of the latter, and means for adjusting said machine angularly relative to said skid to increase the cutting range of said machine in the plane of swinging movement of said bar including a transverse pivot disposed beneath said machine adjacent the center of gravity thereof.
- 20 13. In a mining apparatus, a mining machine normally cutting on its bottom and provided with an angularly adjustable elongated cutter bar provided with cutting elements arranged to cut a kerf to admit said bar, means for operating said machine with its bottom in a vertical plane comprising a skid disposed beneath said machine on which the side of the latter rests, said cutter bar being swingable in a vertical plane extending longitudinally of said skid and between the sides of the latter, and means for adjusting said machine angularly relative to said skid to increase the cutting range of said machine in the plane of swinging movement of said bar including a transverse pivot disposed beneath said machine adjacent the center of gravity thereof.
- 25 14. In a mining apparatus, a mining machine normally cutting on its bottom and provided with an angularly adjustable elongated cutter bar provided with cutting elements arranged to cut a kerf to admit said bar, means for operating said machine with its bottom in a vertical plane comprising a skid disposed beneath said machine on which the side of the latter rests, said cutter bar being swingable in a vertical plane extending longitudinally of said skid and between the sides of the latter, and means for adjusting said machine angularly relative to said skid to increase the cutting range of said machine in the plane of swinging movement of said bar including a transverse pivot disposed beneath said machine adjacent the center of gravity thereof, and adjusting means including a cooperating screw and nut connection pivotally connected respectively to said skid and machine.
- 30 15. In a mining apparatus, a mining machine provided with a cutter bar swingable in a vertical plane, a skid disposed beneath said machine including a bottom plate, parallel plates to which the side of said machine is secured, and transverse bracing members for said bottom plate, and means for adjusting said machine angularly relative to said bottom plate including pivot elements carried by said parallel plates.
- 35 16. In a mining apparatus, a mining machine provided with a cutter bar swingable in a vertical plane, a skid disposed beneath said machine including a bottom plate, parallel plates to which said machine is secured, and transverse bracing members for said bottom plate, and means including a transverse pivot disposed beneath said machine for adjusting the latter angularly relative to said bottom plate.
- 40 17. In a mining apparatus, a skid slidable on the mine bottom, a mining machine having an angularly adjustable elongated cutter bar mounted for swinging movement in a vertical plane extending longitudinally of said skid and between the sides of the latter, said cutter bar being provided with cutting elements arranged to cut a kerf to admit said bar, and means for angularly adjusting said machine relative to said skid to increase the cutting range of said machine in the plane of swinging movement of said bar comprising a horizontal pivotal axis lying outside the body of said machine in a straight line which extends between the machine body and said skid without intersecting the former.
- 45 18. In a mining apparatus, a skid slid-
- 50 55 60 65 70 75 80 85 90 95 100 105 110 115 120 125 130

- able on the mine bottom, a mining machine having an angularly adjustable elongated cutter bar mounted for swinging movement in a vertical plane extending longitudinally of said skid and between the sides of the latter, said cutter bar being provided with cutting elements arranged to cut a kerf to admit said bar, and means for angularly adjusting said machine relative to said skid to increase the cutting range of said machine in the plane of swinging movement of said bar comprising a horizontal pivotal axis lying outside the body of said machine between the latter and said skid, said horizontal pivotal connection including a shaft extending transversely of said skid, and supporting means for said shaft disposed at opposite sides of said machine.
19. In a mining apparatus, a mining machine having an angularly adjustable elongated cutter bar mounted for swinging movement in a vertical plane provided with cutting elements arranged to cut a kerf to admit said bar, a skid, said cutter bar swinging in a plane extending longitudinally of said skid and between the sides of the latter, a pivotal support for said machine on said skid adjacent one end of the latter and beneath said machine, means for moving said machine upon said pivotal support reacting on said skid at a point adjacent the other end thereof, and bracing means for said skid for stiffening the same against bending longitudinally.
20. In a mining apparatus, a mining machine having an angularly adjustable elongated cutter bar mounted for swinging movement in a vertical plane and provided with cutting elements arranged to cut a kerf to admit said bar, a skid, said cutter bar being movable in a plane extending longitudinally of said skid and between the sides of the latter, a pivotal support for said machine on said skid adjacent one end of the latter and beneath said machine, means for moving said machine upon said pivotal support reacting on said skid at a point adjacent the other end thereof, and bracing means for said skid for stiffening the same against bending longitudinally.
21. In a mining apparatus, a mining machine provided with a cutter bar swingable in a vertical plane, a skid disposed beneath said machine including a bottom plate, parallel plates to which said machine is secured, transverse bracing members for said bottom plate, longitudinally extending bracing members for said bottom plate secured to said transverse members, and means including a transverse pivot disposed beneath said machine for adjusting the latter angularly relative to said bottom plate.

In testimony whereof I affix my signature.
MORRIS P. HOLMES.
